RICHARD W. SHOEMAKER, OF TURLOCK, CALIFORNIA

TRANSFORMER CUT-OUT

Application filed May 12, 1928. Serial No. 277,212.

This invention relates to devices for protecting transformers such as are interposed in power lines between the main source of current and the point of consumption to prevent damage to the transformer in the event of an overload due to short circuit or other cause being had in the line beyond the transformer or at the point of consumption.

At present the protecting means used for this purpose is in the form of ordinary fuses, which are a source of annoyance to power companies, as they blow out immediately upon the occurrence of any trouble or overloads in any line supplied by the transformer, no matter how momentary or short-lived this overload may be. Under such operating conditions, therefore, all users of current beyond the transformer or taking from the same are deprived of current until the fuses are replaced, even though the trouble itself is only in one line.

The principal object of my invention, therefore, is to avoid the above objectionable feature by providing a protective cut-out structure so arranged that the circuit to the transformer will not be broken until the overload has continued for a certain length of time, both the amount of overload and the duration of time being adjustable for each application as momentary overloads within reasonable limits are not injurious to a transformer. It is my invention that this cut-out structure will not operate until the overload has existed for a sufficient length of time to endanger the transformer, and, in the event that the overload ceases before such injurious time period has occurred, then the cut-out structure will not function and will remain in substantially the same condition as it was before the application of said momentary overload, which may have ceased to exist either by the operation of individual fuses further removed from the transformer, or by a change in load conditions.

With my improved cut-out structure, therefore, the transformer circuit will be only broken under extreme conditions which are not very likely to be had in ordinary service, while at the same time the cut-out structure functions before any harm can be done

to the transformer due to the overloaded conditions.

A further object of the invention is to provide a device for the purpose so constructed that the functioning of the device, when breaking the transformer circuit only requires the replacing of a single small element to again cause the circuit to be closed and conditions to be rendered normal. This element may be inserted very easily and quickly and its cost is negligible compared to that of the complete fuses ordinarily used and which when once blown must be entirely replaced.

Still another object is to provide a structure for the purpose of such a nature that the amount of overload and the duration of time it will be carried before the circuit is broken, can be altered to suit different conditions.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a plan view of my improved cut-out structure.

Fig. 2 is a side elevation of the same.

Fig. 3 is a cross section on the line 3—3 of Fig. 1.

Fig. 4 is a diagram of a transformer and its circuit as connected with my cut-out device.

Fig. 5 is a side elevation of a modified form of the device, for heavy duty purposes.

Referring now more particularly to the characters of reference on the drawings, and particularly at present to Figs. 1-4, the device comprises a base panel 1 of insulation material, on which are mounted in transversely spaced and parallel relation, two pairs of longitudinally aligned and separated contact strips 2. These strips are separately secured at their opposite ends to the panel in spaced relation thereto by terminal posts 3 and 4. The corresponding pairs of contacts

are adapted to be bridged and engaged by contact plates 5 which are mounted on stems 6 projecting at right angles from said plates. These stems are slideable through a cross bar 7 of insulation material which is disposed some distance from and parallel to the panel, the stems having nuts 8 some distance outwardly of the bar. Compression springs 9 disposed about the stems between the bar and the plates 5 act to press the latter firmly against the contacts when the bar is held stationary at such a distance from the panel that the springs are then under a certain compression.

The bar is thus normally held so as to maintain the contacts 2 engaged by the plates 5 by the following means: mounted on the panel between the pairs of contacts is a rigid metal block 10 of iron or the like which intermediate its ends has a circular socket 11 open to the top of the block. The block is preferably ribbed as shown so as to provide a heat radiating surface of sufficient area to prevent the block from heating too rapidly and to too great an extent. Removably seated in and closely fitting the socket is a plug 12 of very soft metal alloy of special character. This plug preferably has a melting point approximately 200° F., though such point may be altered by altering the composition of the alloy to harden or soften the same somewhat. A hard metal stem 13 is connected to the plug and projects upwardly through the bar 7, this stem having adjustable nuts 14 thereon above the bar and engaging the same. The block is provided with a removable cover plate 15 having an orifice 16 about the stem 13 which is concentric with but somewhat smaller than the socket and plug.

Extending under the block between the same and the panel and insulated from the block and from each other are transversely spaced heating or resistance elements 17 of suitable character, which at one end are connected to separated binding posts 18 on the panel and at the other end are connected in common to a single binding post 19.

The cut-out device is particularly adapted to be mounted in connection with a transformer T such as used to transform current from high voltage power lines to 110 V. or 220 V.; or to 220 V. or 440 V. depending on the capacity of the transformer used. Standard transformers are made so that any one may be connected to supply either one of the two correlated voltages; but special six-lead transformers are also made so as to be connected to supply either 110 V., 220 V., or 440 V. as may be desired. In such a case, the primary winding 20 of the transformer is connected to the power lines 21, while the secondary windings 22 of the transformer are connected at their opposite ends to the terminal posts 3, and at their adjacent ends

to the binding posts 18 of the resistance elements in crossing relation.

The house or consumer's wires 23 are connected to the terminal posts 4 and to the binding post 19 of the elements 17. This arrangement, as will be evident to one skilled in the art enables the lines 23 to be coupled up so as to use either 110 V or 220 V or 440 V current by means of standard or special transformers constructed to suit, as above stated.

By means of this arrangement of the cut-out structure in connection with the transformer, it will be seen that the current flowing from the secondary windings of the transformer through the wiring 23 will pass through the resistance elements, heating the same. These elements and the block 10, however, are so designed that under normal conditions the heat generated and imparted to the block is insufficient to melt or appreciably soften the plug, and consequently the contact plates 5 are maintained in engagement with the contacts 2 and the circuit from the transformer to the wiring 23 remains closed.

When an overload or short circuit is present in the wiring 23 however, the heat generated by the elements 17 is greater. Therefore, after this overloading condition has continued for a certain length of time, the block 10 will be heated to a considerable degree above its normal heat, causing the plug 12 to be so softened that the strength of the springs 9 will be sufficient to shear the sides of the plug around the rim of the overhanging orifice 16 of the retaining plate. This of course will cause the plug to be drawn out of its socket in the block and there is then nothing to hold the bar 7 to the other parts of the structure. The springs are then free to act, first pushing the bar against the nuts 8 and then causing the bar and all parts connected thereto to jump clear of the remainder of the structure and the bridging of the contacts 2 to be broken. The circuit to the transformer is thus broken before any harm is done.

This breaking of the circuit, however, does not take place immediately upon the short circuit being had as is the case with ordinary fuses, since it takes an appreciable time for the block to heat sufficiently to cause the plug to soften to the extent necessary to cause it to shear past the retaining plate. When the plug is thus sheared off and the circuit broken, it is only necessary to remove the retaining plate 15, mount another plug on the stem 13, press down the new plug into the socket and replace the plate, the contact plates then of course automatically resuming their bridging engagement with the contacts. This plug, or at most the plug and its stem are the only new parts to be supplied after the structure has functioned in a pro-

tecting manner, and the cost of which parts is very little as will be evident.

It will be noted that the springs have a double function, serving not only to yieldably press the contact plates against the contacts 2, but also acting to throw the bar 7 and consequently said contact plates, clear of the structure when the block is sheared off.

The cut-out point in relation to the time and heat necessary may be varied by changing the loss in the heater elements; the size and shape of the block; the temperature of the melting point of the plug; and by adjusting the nuts on the plug stem so that the strength of the springs, which maintains the plug in shearing engagement with the retaining plate, is altered. It will be also noted that the plug is mounted and used not as a solder, or as a current carrying element but as a section in shear.

It will also be seen that when the shearing action occurs, though the shearing movement itself may take place slowly, the final separation of the contact plates 5 from the contacts 2 will be almost instantaneous due to the sudden release of the springs when the plug is fully sheared off. There is therefore no arcing at the contacts at the instant of breaking of the circuit.

The above described apparatus is suitable for ordinary current capacities. For small sizes and capacities, the plates 5 would be as shown, while for larger capacities, said plates should be of laminated construction.

For very heavy duty, however, I preferably employ the structure shown in Fig. 5. In this modified form of the device the holding plug stem 13^a is connected to one end of a lever 24 which is pivoted at its opposite end on the base panel 1^a. Intermediate its end this lever has a cross bar 7^a mounted thereon, which bar supports the switch plate stems 6^a. The functioning of this structure is substantially the same as that above described as will be evident, with the exception that the lever being pivoted onto the panel does not ever become actually disassociated from the panel.

In both forms of the device, the panels are intended to be mounted in a vertical position, so that when the circuit is broken the switch or contact plates of either type will be positively thrown clear of the contacts.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what

I claim as new and useful and desire to secure by Letters Patent is:

1. A transformer cut-out including a pair of spaced contact members, a plate to engage and bridge the same; supporting means for the plate, means acting on said supporting means tending to force the same away from the contacts, resistance elements arranged to be interposed in the circuit from the secondary winding of a transformer in which said contacts are interposed, and means actuated by the heat generated by said elements to permit said supporting means to move away from the contacts when the elements are heated to a predetermined degree and for a predetermined period of time. 70

2. A transformer cut-out including a pair of spaced contact members, a plate to engage and bridge the same, supporting means for the plate, a soft-metal plug, means connecting said plug to the supporting means, means arranged in connection with the plug to normally retain the same in shearing relation therewith, means acting on the supporting means, tending to move the same away from the contacts and placing a shearing strain on the plug, and means for heating and softening the plug, said heating means and contacts being adapted to be interposed in the circuit from the secondary winding of a 80 transformer. 85

3. A transformer cut-out including a pair of spaced contact members, a plate to engage and bridge the same, supporting means for the plate, a soft-metal plug, means connecting said plug to the supporting means, a relatively hard block in the outer face of which said plug is mounted, an orificed member mounted on the outer face of the block; the orifice alining with and overhanging the side edges of the plug, means acting on the supporting means to move the same away from the block, and heating elements associated with the block and adapted to be interposed in the circuit from the secondary winding of a 100 transformer and in which circuit the contacts are also interposed. 105

4. A transformer cut-out including a pair of spaced contact members, a plate to engage and bridge the same, a stem projecting from the plate in the direction opposite to the contacts, a bar through which the stem is slideable, a compression spring between the plate and bar, another stem secured to and depending from the bar, a soft metal plug fixed on said other stem, a retaining plate fixed with respect to the contacts and disposed between the plug and bar, said retaining plate having an orifice alined with and overhanging the sides of the plug, and electric means for heating the plug under certain conditions sufficient to cause the plug to shear past the retaining plate with the pull of the spring thereon, said contacts and heating means being adapted to be interposed in the circuit 115 120 125 130

from the secondary winding of a transformer.

5. A transformer cut-out including a pair of spaced contact members, a plate to engage and bridge the same, a stem projecting from the plate in the direction opposite to the contacts, a bar through which the stem is slideable, a compression spring secured to and depending from the bar, a soft metal plug fixed 10 on said other stem, a retaining plate disposed between the plug and bar and having an orifice overhanging the side edges of the plug, a relatively hard block fixed with respect to the contacts, the plate being fixed on the 15 block and the latter having a socket in which the plug is disposed, and electric heating means arranged in connection with the block to heat the same, said contacts and heating means being adapted to be interposed in the 20 circuit from the secondary winding of a transformer.

In testimony whereof I affix my signature.

RICHARD W. SHOEMAKER.
